UNITED STATES PATENT OFFICE.

HENRY G. SAAL, OF CHICAGO, ILLINOIS.

DESIGN FOR A MOUNTING-FRAME FOR SPRING-MOTORS.

55,648.

Specification for Design.

Patented July 6, 1920.

Application filed November 17, 1919. Serial No. 338,767. Term of patent 14 years.

To all whom it may concern:

Be it known that I, HENRY G. SAAL, a citizen of the United States, residing at Chicago, in the county of Cook and State of Illinois, have invented a new, original, and ornamental Design for a Mounting-Frame for Spring-Motors, of which the following is a specification, reference being had to the accompanying drawing, forming part thereof.

Mechanical features of the construction shown are claimed in my co-pending appli-

cation executed of even date herewith, Case 3.

Figure 1 is a perspective view taken from one corner of the frame showing my new design and Fig. 2 is a perspective view taken from the corner of the cabinet which is diagonally opposite that from which Fig. 1 is taken.

I claim:

The ornamental design for a mounting frame for spring motors, as shown.

HENRY G. SAAL.
